United States Patent Office

Des. 233,829

Patented Dec. 3, 1974

233,829

JAR OR SIMILAR ARTICLE

Sara L. Balbach, New York, and Richard W. Greger,
Corning, N.Y., assignors to Corning Glass Works,
Corning, N.Y.

Original design application July 20, 1970, Ser. No.
24,040, now Patent No. 225,309. Divided and this
application Sept. 27, 1971, Ser. No. 184,334

Term of patent 14 years

Int. Cl. D9—01

U.S. Cl. D9—164

Fig. 1

Fig. 4

Fig. 6

Fig. 5

FIG. 1 is a side elevational view of a jar or similar article embodying our new design, the opposite side being the same in appearance as the side shown.

FIG. 2 is a side elevational view of another embodiment, the opposite side being the same in appearance as the side shown;

FIG. 3 is a side elevational view of an additional embodiment, the opposite side being the same in appearance as the side shown;

FIG. 4 is a top plan view;

FIG. 5 is a bottom plan view; and

FIG. 6 is a side elevational view showing a still further embodiment of our new design, wherein the ornamentation seen in FIG. 1 appears only on the side opposite that shown.

The characteristic feature of the design resides in the particular surface ornamentations shown.

This application is a division of application Ser. No. D. 24,040, filed July 20, 1970, now Pat. No. D. 225,309. We claim:

The ornamental design for a jar or similar article, as shown and described.
